ABSTRACT

A lightweight deflating rectangular bag made of a leak and puncture resistant mattress film with a plastic two-way valve for lowering of caskets for entombment in below-floor level “Westminster” crypt locations. The deflating bag is configured to lower a casket, in a safe, dignified, and simple manner, into a subterranean crypt for final entombment, while family members, relatives, and friends observe during this important moment in the funeral service.

DEFLATING RECTANGULAR BAG WITH RELEASE VALVE, AND METHOD FOR USE TO LOWER A CASKET INTO A FRONT- OR SIDE-FACING SUBTERRANEAN CRYPT

CROSS-REFERENCE TO RELATED APPLICATION

This application claims the benefit of the earlier filing date of U.S. Provisional Patent Application No. 62/883,169 filed on Aug. 6, 2019, the disclosure of which is incorporated by reference herein.

FIELD

Exemplary embodiments of the disclosure relate to the field of mortuary science, caskets and lowering apparatus, and in particular an apparatus and method for use in connection with lowering caskets during a funeral service for entombment in front- or side-facing subterranean mausoleum crypts.

BACKGROUND

Two devices and methods of lowering caskets into front-facing subterranean crypts are known. Each method relies on both significant lifting manpower and persons entering the confined space of the crypt. The second method further uses non-standardized materials and methods. The first is a mechanical device that is a track and roller mechanical assembly consisting of two rear posts, a front frame, a top frame with track, and a top frame with rollers and straps that rests on top of the casket. Once assembled two handles on the top frame lower the casket into the subterranean crypt chamber. This device is designed only for front-facing subterranean crypts. See FIGS. 12A-12C.

The second method involves placing one or two pieces of 2"×4" or 2"×6" lumber, metal, or other material at an angle resting on the front lip of the crypt and extending halfway into the floor of the crypt. The casket is then placed on top of the boards and slid down into the crypt. Then two people hold onto the front handle of the casket, either with their hands or to a rope or other straps tied to the handle, and lift the casket in the air. One person then removes the lumber that was used to support the casket, and the two people holding the casket lower it the remainder of the distance into the crypt. This method can be used for both front- and side-facing subterranean crypts. See FIG. 13.

BRIEF DESCRIPTION OF THE DRAWINGS

FIG. 1 shows a perspective view of a deflating bag before being inflated according to exemplary embodiments.

FIG. 2 shows a perspective view of the deflating bag of after being inflated to 95% capacity.

FIG. 3 shows a front view of the deflating bag placed inside the subterranean crypt chamber.

FIG. 4 shows a front view of a 22"×75" particleboard panel placed on top of the deflating bag for additional support and to facilitate the sliding of the casket completely inside the subterranean crypt chamber.

FIG. 5 shows a perspective view of the casket after having been slid partially inside the crypt chamber.

FIG. 6 shows a detail view of the plastic valve used to inflate and deflate the deflating bag.

FIG. 7 is a diagram that shows the pattern used during the manufacturing process.

FIG. 8 is a detail view of the valve assembly during the manufacturing process.

FIG. 9 shows a top view of the device compressed, folded, and packaged for shipping and storage.

FIG. 10 shows a front view of the device inflated and rotated horizontally inside of a "couch" style subterranean crypt.

FIG. 11 shows a front view of the casket on top of the inflated device inside of a "couch" style subterranean crypt.

FIGS. 12A-12C show front, front perspective and side perspective views of a first prior art method.

FIG. 13 shows a front view of the second prior art method.

DETAILED DESCRIPTION

15 Exemplary embodiments of the disclosure provide a light-weight deflating rectangular bag with a release valve for the lowering of caskets for entombment in, for example, below-floor level "Westminster" crypt locations. The exemplary embodiments are configured to lower a casket into a subterranean crypt for final entombment, while family members, relatives, and friends observe during this important moment in the funeral service in a safe, dignified, and simple manner.

20 As shown in FIG. 1, an exemplary embodiment is configured as a rectangular shaped deflating bag 10 with a circular two-way valve 14 depicted in FIG. 6, wherein deflating bag 10 is configured to be inflated to an inflated state and deflated to a deflated state. For assembly of 25 deflating bag 10, mattress film 12 is cut and folded, as shown in FIG. 7, and the perimeters heat-sealed together. Deflating bag 10 may have the dimensions of 78"×23"×28", for example, forming a rectangular parallelepiped shape. In 30 embodiments a deflating bag 10 may have dimensions of about 78"×23"×28" when inflated; as one of skill in the art will recognize that these dimensions may vary slightly depending on the extent to which one inflates a deflating bag 10, whether its overinflated or underinflated during actual use. One of skill in the art will also recognize that air 35 expands and contracts depending on temperature such that dimensions of an inflated deflating bag 10 may vary after inflation as temperature fluctuates; nevertheless, the nominal dimensions of the bag remain substantially 78"×23"×28" when inflated. Deflating bag 10 may be made of leak and 40 puncture resistant material such as 14.5 mil. mattress film 45 12. A cutout 26 is made for two-way valve 14 as shown in FIG. 8. Deflating bag 10 is compressible and foldable for shipping and storage as shown in FIG. 9.

The method of lowering the casket 20 into a front-facing 50 subterranean crypt 16 involves inflating the deflating bag 10 to 95% capacity as shown in FIG. 2 forming a substantially rectangular parallelepiped shape, placing deflating bag 10 inside the subterranean crypt 16 as shown in FIG. 3, placing 55 a board 18 on top of the inflated deflating bag 10 as depicted in FIG. 4, placing the casket 20 on top of a furniture dolly 22, rolling the casket 20 to the front of the crypt 16 and placing the casket 20 on top of the board 18 as shown in FIG. 5 and releasing the plastic valve 14 to deflate the bag 10. Board 18 may be a 22"×75" particleboard, for example.

The method for lowering the casket 20 into a side-facing 60 subterranean crypt 24 involves inflating deflating bag 10 to 95% capacity, placing deflating bag 10 inside the subterranean crypt 24 as shown in FIG. 10, orienting the inflated deflating bag 10 such that the plastic valve 14 is facing 65 towards the front of the crypt 24, placing a board 18 on top of the inflated bag 10, placing the casket 20 on top of a standard furniture dolly 22, rolling the casket 20 to the front

of the crypt 16 and placing the casket 20 on top of the board 18 as shown in FIG. 11 and releasing the plastic valve 14 to deflate the bag 10. Board 18 may be a 22"×75" particle-board, for example.

Exemplary embodiments require significant less manpower and improve upon the safety, dignity, and feasibility of lowering the caskets.

Nothing in the above description is meant to limit the invention to any specific materials, geometry, or orientation of elements. Many part/orientation substitutions are contemplated within the scope of the invention and will be apparent to those skilled in the art. The embodiments described herein were presented by way of example only and should not be used to limit the scope of the invention.

Although the invention has been described in terms of particular embodiments in this application, one of ordinary skill in the art, in light of the teachings herein, can generate additional embodiments and modifications without departing from the spirit of, or exceeding the scope of, the described invention. Accordingly, it is understood that the drawings and the descriptions herein are proffered only to facilitate comprehension of the invention and should not be construed to limit the scope thereof

What is claimed is:

1. A method of lowering a casket for final entombment into a subterranean crypt comprising:
 25 inflating a bag configured to support the casket within the subterranean crypt;
 placing the inflated bag inside the subterranean crypt;
 placing a board on top of the inflated bag;
 placing the casket on top of the board;
 deflating the inflated bag for lowering the casket within
 30 the subterranean crypt.

2. The method of claim 1 wherein inflating the bag comprises inflating the bag to 95% capacity.

3. The method of claim 1, prior to placing the casket on top of the board, further comprising orienting a valve of the bag to the front of the crypt.

4. The method of claim 1, prior to placing the casket on top of the board, further comprising:

placing the casket on top of a dolly; and
 rolling the casket on the dolly to the crypt.

5. The method of claim 4, wherein the subterranean crypt is a side-facing subterranean crypt, and wherein the casket is placed on the dolly in a side-facing manner.

6. The method of claim 1, wherein the subterranean crypt is a front-facing subterranean crypt.

7. The method of claim 1, wherein the subterranean crypt is a side-facing subterranean crypt.

8. The method of claim 1, wherein the bag in the inflated state is configured to have interior dimensions of the subterranean crypt.

9. The method of claim 1, wherein the bag in an inflated state has the dimensions of 78"×23"×28".

10. The method of claim 1, wherein the bag in an inflated state has the dimensions of about 78"×23"×28".

11. The method of claim 1, wherein the bag is formed of a leak and puncture resistant material is 14.5 mil. mattress film.

12. The method of claim 1, wherein the bag has a two-way valve configured for inflation and deflation of the bag, wherein deflating the inflated bag comprises releasing the two-way valve.
